R. HART

MEANS FOR PHOTOGRAPHICALLY RECORDING SOUND

Filed April 9, 1923

UNITED STATES PATENT OFFICE.

RUSSELL HART, OF LOS ANGELES, CALIFORNIA.

MEANS FOR PHOTOGRAPHICALLY RECORDING SOUND.

Application filed April 9, 1923. Serial No. 630,870.

My invention relates to means for photographically recording sound modulated light variations upon a moving sensitized film; and among my salient objects are, first, to provide a way for modifying the image of a constant light source in such a manner that its total actinic value will always be proportionate to the corresponding ordinate of the sound wave being recorded; second, to secure 10 virtual coincidence between the sound waves and the corresponding modified actinic values of the image; and, third, to afford facilities for continuously photographing the modified image in such a manner as to constitute a complete and undistorted record of the sound waves.

Other important objects are to supply a method for producing a sound record of great sharpness adapted, for example, for 20 practically perfect reproduction of articulated voice; and to accomplish the recording at a film speed corresponding to that commonly employed in the taking of motion pictures.

Still further objects and advantages of my invention will appear hereinafter, and while I show herewith and will describe a preferred form of construction, I desire to be understood that I do not limit myself to 30 such form, since various changes and adaptations may be made therein without departing from the spirit of the invention as hereinafter claimed.

It is well known that a true graphical representation of sound waves comprises a more or less complex curve in which the variation in value of the ordinates corresponds to variations in sound pressures. The position of the axis of abscissæ has no effect upon the 40 shape of the curve, and may be taken so that the curve is wholly above the axis. The area below such a curve, above the axis, may then be considered as made up of an infinite number of vertical elementary strips of infinitesimal width, with no gaps or spaces between.

A similar area will be produced if we continuously photograph a luminous line of varying length upon a film moving at a constant speed, provided the image of the line is parallel to the film and perpendicular to the direction of its motion. If the image of such a line is extremely thin, and if its length is at all times proportional to the corresponding ordinate of the above described curve, we shall have one margin of the photo-

graphed area bounded by a curve that truly represents the sound wave. This photographed area is adapted for reproduction of the original sound, by methods that have 60 been developed.

The present invention concerns itself with means for photographically recording sound waves in the manner just described, and in the embodiment selected for illustrative purposes as disclosed in the accompanying drawing.

Figure 1 is a sectional elevation of the complete device, the sectional plane corresponding in position to the line 1—1 of 70 Fig. 2;

Figure 2 is a sectional plan view of a portion of the apparatus taken on the line 2—2 of Fig. 1; showing details not included in the other figures of the drawing; 75

Figure 3 is a fragmentary interior elevation of the recording end of the apparatus taken on the line 3—3 of Fig. 1;

Figure 4 is an enlarged side view of a preferred form of light source having certain 80 characteristics that particularly fit it for the purpose herein described;

Figure 5 is an enlarged elevation of the light modulating head, shown in central section; 85

Figure 6 is a much magnified diagrammatic view of the modulating shutter, or target; and

Figure 7 is a plan view of a portion of a sound record made upon a motion picture 90 film in accordance with my improved means.

Similar reference numerals refer to similar parts throughout the several views.

Before passing to a detailed description of my apparatus it should be understood that 95 the present invention involves only a means for photographically recording sound waves. It does not concern itself with reproduction of the sound except to produce a record adapted for such reproduction by practical 100 methods that have been devised.

Referring to Fig. 1 of the drawing it will be noted that, in the form of my invention herein described, the apparatus is mostly contained within two elongated light-proof 105 box structures, or cameras, 8 and 9. The first of these is used in a horizontal position and preferably is fixedly mounted on a substantial pedestal 10 in such location and manner as not to be subjected to the effects 110 of external mechanical vibrations. This is the light modulating portion of the appa-

ratus. Camera 9, containing the recording equipment, is adapted for being removably mounted in a vertical position on a depressed step 11 of the pedestal; and for being accurately positioned vertically and transversely thereon as by a pair of rails, one of which is shown at 12. The positioning is such that the longitudinal center lines of the two cameras intersect at right angles, and the transverse center line of camera 9 coincides with the longitudinal center line of camera 8.

Microscopic focusing of both cameras is made prior to recording and this is done in sequence. Camera 8 is focused first, with 9 slid back on the rails out of the way, or removed from its step on the pedestal entirely. After 8 is properly focused, 9 is carefully slid on the rails up against it, and the two cameras are then firmly bolted or latched together prior to the focusing of 9. One method of attaching the cameras together is by means of lugs as indicated in plan view at 13 in Fig. 2.

For the light source I employ a special tubular gas filled lamp L plainly illustrated in Fig. 4. This contains a single linear tungsten filament 14, of very small diameter and capable of being operated at a high temperature. This filament is stretched between a longitudinal terminal 15 and a resilient transverse terminal 16, in such a manner as to be under spring tension at all times, so as to prevent its sagging when operated in a horizontal position. The maximum bending moment of terminal 16 occurs at the point where it is sealed into the glass tube of the lamp. This point is at a considerable distance from the hot filament, and therefore not subjected to great temperature. Moreover the terminal may be a relatively wide flat strip having considerable radiating surface. For these reasons the terminal does not become annealed and it retains its resiliency indefinitely. This lamp is mounted in a clamp 17 in the center of one inside end of camera 8, in such a manner that the filament intersects the longitudinal axis of the camera at right angles, and may be adjusted to a horizontal position as by the wing nut 18.

The modulating means I employ comprise a modulating head 19 and a diaphragm 20, of ordinary acoustic construction, as illustrated in Fig. 5. They are used in such position that the diaphragm is horizontal. The head is connected to a sound tube 21 and sound horn 22 in any suitable manner, as by the telescoping swivel joints illustrated. In the center of the diaphragm is mounted a small stiff post 23, carrying a very small razor-edged target 24 at its upper extremity. The razor edge 25 is either ground, or mounted, in a slightly oblique position as illustrated most clearly in the magnified

view of Fig. 6, and adjustment means 26 are provided for bringing the center of edge 25 in exact coincidence with the longitudinal axis of the camera. The sound waves, incoming through horn 22 and tube 21, impinge against the under surface of diaphragm 20, and the resulting vibration of the latter causes razor edge 25 to cut more or less deeply across the horizontal axial plane of the camera. The oblique angular edge of the target permits a very small vertical movement of the latter to make a relatively great variation in the length of this cut.

Intermediate the light source and the modulating means is a lens arrangement 27, adapted for focusing in a convenient manner as by racks and pinions 28, and hand-wheel 29. This lens group is mounted coaxial with the camera.

The image of the light source, after the filament has been adjusted horizontally intersecting the camera axis, is focused upon razor edge 25 by means of the lens group 27. This is accomplished with great accuracy by means of a portable microscope 30, adapted for inserting in the fixed tube 31 which is mounted on the end of the camera for this purpose. The microscope is first focused on the razor edge, and then hand-wheel 29 is adjusted until the image of the light source appears sharp in the microscope without changing its focal adjustment.

Camera 9, as shown in Fig. 1, is partitioned horizontally in such a manner as to form reel boxes 32 at its upper and lower extremities. Access to these is had through side opening doors 33. The reel boxes communicate with the central chamber 34 only by means of small narrow slits 35 adapted for the passage of the photographic film strip 36.

For photographically recording sound the film strip must be given a continuously uniform motion, and I prefer to employ a synchronous motor for this purpose. The driving means must be positive in character, and the film must be constrained to lie perfectly flat at the point where it is being exposed. It must also be prevented from "chattering", or vibrating as the result of friction.

I employ ordinary reels 37 for the film; any suitable type of feed sprockets 38, guide rollers 39, and pressure gate device 40. The feed sprockets are gear connected as shown at 41, and the driving power is applied to sprocket shaft 42 by means of the gear 43. The other sprocket shaft 44 carries a pulley 45, by means of which the take-up reel may be yieldingly driven.

While being exposed, the film in the gate mechanism passes between two polished plates 46 and 47. These are pressed together by light helical springs surrounding

the guide screw studs 48 in the manner common to the art. Flatness of field is positively attained in this way, the exposure being had through small apertures 49 in the plates in front of the film. Plate 47, behind the film, is also similarly apertured to permit focusing in a manner that will be explained presently.

A tube 50 is mounted at the rear center of camera 9 for the purpose of inserting microscope 30; and a suitable lens group 51 is tubularly mounted at the front inside center for the purpose of transferring the modified image of the filament from razor edge 25 to the sensitized surface of the film strip. Focusing of this lens group is accomplished by the rack and pinion movement 52.

I have devised a particularly delicate and satisfactory method for obtaining an accurate focus of the transferred image upon the sensitized surface of the film. For this purpose I first place a piece of exposed film between plates 46 and 47 and, after inserting the microscope in tube 50, I focus it carefully upon the metallic crystals in the exposed surface, as viewed from the rear through the aperture in plate 47 and the transparent material of the film. I then pull out the exposed film and move camera 9 to its operating position against camera 8, and adjust focusing screw 52 until the transferred image of the light source appears sharp in the microscope; meanwhile allowing the focal adjustment of the microscope to remain undisturbed. The unrecorded film strip is then placed in the apparatus and recording can commence.

The main features of the construction and operation of my invention will be clearly apparent from the foregoing description, but it is desired to call especial attention to certain of the refining features that might otherwise be overlooked.

Chief among these refinements is the very delicate method of modulating the actinic value of the light image. By referring to the much magnified view of the target, as shown in Fig. 6, it will be seen that a vertical movement equal in total to the distance between arrow heads 53, serves to completely eclipse the full length of the image, which is indicated by 54. By reducing the angle of obliquity of razor edge 25, a still smaller vertical movement of the target will serve to eclipse the image. The angle of obliquity can easily be made adjustable if desired, as by the screw 55 clamping the slotted end 56 of target post 23.

A second refinement is the possible de-magnification of the luminous filament at the razor edge. If the diameter of the filament is in reality, say, one thousandth of an inch, and the ratio of de-magnification is one to four, then the virtual diameter of the image will only be one-four-thousandth of

an inch. This is so small that for practical purposes it closely approaches the width of the infinitesimal strips mentioned in the theoretical discussion of the subject in the early part of this specification.

A third refinement comprises the methods of microscopic focusing. An image of the luminous filament is first very accurately focused in the plane of the razor edge, so that the point where the edge eclipses the light rays is very sharply defined. This primary image is then thrown as a secondary image upon the sensitized film, exactly focused in its plane, by the method described above. The resulting photographed record is much sharper than it would be possible to make it if the razor edge merely intercepted the unfocused rays from the light source.

As previously pointed out, the sound record made in the manner described, and illustrated in Fig. 7, comprises a photographed area 57, bounded on one side by a complex curve 58, truly representing the sound waves. The possible sources of distortion of the record are practically negligible, and reside chiefly in the inherent qualities of the diaphragm with its post and target. The inertia of these parts may be made very small, and their natural vibration period kept outside of the ordinary range of the sounds to be recorded.

It will be obvious that such changes as electro-magnetic operation of the modulating diaphragm; lever magnification of the razor edge movement; method of mounting the light intercepting target on the diaphragm; and details of arrangement and adjustment of parts; fall within the scope of my invention.

In a companion application, filed December 22, 1922, Serial Number 608,499, I disclosed certain features of construction herein shown but not claimed in this application.

I claim:

1. Apparatus of the character described, comprising; a luminous rectilinear filament of great tenuity; a lens for focusing an image of the filament in a plane; a target vibratile to sound in said plane for variably eclipsing the light rays forming said image to vary the length of the image; a photo-sensitized surface, movable parallel to said plane; and a second lens for projecting a secondary image of the variable first image upon the sensitized surface, transversely to its direction of motion.

2. Apparatus of the character described, comprising; a luminous rectilinear filament of great tenuity, angularly adjustable about a transverse axis; a lens for focusing an image of the filament in a plane; a target vibratile to sound in said plane for variably eclipsing the light rays forming said image

to modify the length of the image visible beyond said plane; a photo-sensitized surface, movable parallel to said plane; and a second lens for projecting a secondary image 5 of the variable first image upon the sensitized surface, transversely to its direction of motion.

3. Apparatus of the character described, comprising; a luminous filament of great 10 tenuity, angularly adjustable about a transverse axis; a lens for focusing an image of the filament in a plane; a target vibratile to sound in said plane for variably eclipsing the light rays forming said image to modify 15 the length of the image visible beyond said plane; a photo-sensitized surface, movable parallel to said plane; and a second lens for projecting a secondary image of the variable first image upon the sensitized surface trans- 20 versely to its direction of motion; said target having a ray intercepting edge variably oblique to the first image.

4. The combination of a luminous rectilinear filament with; a lens adapted for fo-

cusing an image of said filament in a plane; 25 a target vibratile to sound in said plane having an edge obliquely intersecting said image; a photo-sensitized surface uniformly movable parallel to said plane and spaced therefrom; and a second lens intermediate 30 the target and sensitized surface whereby a combined image of the target and filament image may be focused upon said sensitized surface.

5. The combination of rectilinear luminous filament of great tenuity with; means 35 for focusing an image of the filament in a plane; means in said plane, vibratile to sound, for variably eclipsing the light rays to modify the length of said image visible 40 beyond the plane; a photo-sensitized surface, movable parallel to said plane; and means for projecting a secondary image of said modified primary image upon said sensitized surface, transversely to its direction 45 of motion.

RUSSELL HART.
